(57) **CLAIM**

The ornamental design for a textile printing machine as
shown and described.

DESCRIPTION

FIG. 1 is a front, right-side, top perspective view of a textile
printing machine showing the new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and,
FIG. 7 is a front, left-side, top perspective view thereof.
The broken lines depict parts of the textile printing machine
that form no part of the claimed design. The dot-dash chain
lines depict boundaries of the claimed subject matter, and
thus form no part of the claimed design.
